Primary Examiner — Ian Simmons*Assistant Examiner* — Dana L Meyrow(74) *Attorney, Agent, or Firm* — Foley & Lardner LLP(57) **CLAIM**

I claim the ornamental design for a perfume bottle, as shown and described.

DESCRIPTION

FIG. 1 is a perspective view of a perfume bottle of the claimed design;

FIG. 2 is a front elevation view thereof, the left side, right side and rear elevation views being identical;

FIG. 3 is a top plan view thereof;

FIG. 4 is a bottom plan view thereof, shown at an enlarged scale;

FIG. 5 is an enlarged detail view of a portion of the perfume bottle taken from FIG. 3; and,

FIG. 6 is an enlarged detail view of a portion of the perfume bottle taken from FIG. 1.

The ornamental design which is claimed is shown in the drawings in solid lines. The broken lines in FIGS. 1, 3, 5 & 6 define the area of the detail views and form no part of the claimed design.
